UNITED STATES PATENT OFFICE.

WILLIAM THOMAS FINNELL, OF OAKLAND CITY, INDIANA, ASSIGNOR OF
ONE-HALF TO N. B. WILSON, OF SAME PLACE.

DITCHING-MACHINE.

SPECIFICATION forming part of Letters Patent No. 360,870, dated April 12, 1887.

Application filed August 17, 1886. Serial No. 211,152. (No model.)

To all whom it may concern:

Be it known that I, WILLIAM THOMAS FINNELL, a citizen of the United States, residing at Oakland City, in the county of Gibson and State of Indiana, have invented a new and useful Improvement in Ditching-Machines, of which the following is a specification.

My invention relates to improvements in ditching-machines; and it consists in the peculiar construction and combination of devices, that will be more fully set forth hereinafter, and particularly pointed out in the claims.

In the drawings, Figure 1 is a side elevation of a ditching-machine embodying my improvements. Fig. 2 is a top plan view of the same. Fig. 3 is a vertical longitudinal section, and Fig. 4 is a transverse section taken on the line *xx* of Fig. 2.

A represents the main frame of the machine, which consists of the side beams, *B*, that are connected together by the transverse beams *C*, and at their front ends by a transverse beam, *D*, and a bolster, *E*.

F represents a horizontal longitudinal guideway, which is secured on the two beams *C* nearest the rear ends of the side beams, and in the said guideway slides a block, *G*, having projecting flanges or keepers *H*, that bear upon the upper sides of the guideway, so as to support the block. To the front end of this block is hinged a hand-lever, *I*.

K represents the front axle, which is pivoted to the front end of the machine-frame by a king-bolt, which passes down through the beam *D* and the bolster *E*. On the front axle are mounted supporting-wheels *L*.

M represents the rear axle, which is bolted to the under sides of the side beams at a considerable distance from the rear ends thereof. On the rear axle are journaled supporting-wheels *N* and *O*. The wheel *N* on the right-hand side of the frame is secured to the gear-wheel *P*, or the said gear-wheel may be formed integrally with the wheel *N*, and thereby caused to rotate therewith. To the wheel *O* is attached a sprocket-wheel, *R*.

S represents a pair of brackets, which are bolted on the upper sides of the beams *B*, at the rear ends thereof, the said brackets extending rearwardly beyond the rear ends of the said beams and having supporting-arms *S'*. On the upper sides of the brackets *S*, near

their front ends, are formed bearings *S''*, in which is journaled a transverse shaft, *T*. On one end of the said shaft is secured a small sprocket-wheel, *T'*, which is connected to the wheel *R* by means of an endless chain, *T''*. The shaft *T* is also provided with a gear-wheel, *T''*.

U represents a transverse shaft, which is journaled in the brackets *S* in rear of the shaft *T*. To one end of the said shaft *U* is rigidly secured a gear-pinion, *U'*, which meshes with the gear-wheel *T''*.

V represents an elevating-trough, which has its rear upper end hinged on the shaft *U*, and the central portion of the shaft *U*, between the sides of the trough, is provided with a drum or roller, *U''*. In the lower front end of the trough *V* is journaled a transverse roller, *V'*.

V'' represents an endless carrier-apron, which connects the rollers *V'* and *U''*, and forms the bottom for the elevating-trough.

X represents an elevating-rod, which passes through an opening made in the sliding block *G*. This rod is provided with a series of openings, *X'*, and its lower end is bifurcated to form depending arms *X''*.

Y represents a plow-beam, which is provided with rearward and downwardly extending standards *Y'*, which are pivoted to the lower ends of the arms *X''* of the elevating-rod. Between the lower ends of the said standards is secured an inclined plow, *Y''*, the front end of which is beveled on opposite sides to a central point. These beveled edges are sharpened. From the under side of the plow, near the upper end thereof, depends a curved guard, *Y'''*, which is adapted to the contour of the front end of the endless carrier, and the lower edge of this guard-plate is on the same plane with the point of the plow, and thereby moves in the bottom of the furrow made by the plow. From the ends of the guard-plate *Y'''* extend rearwardly-projecting arms *X'''*, having their rear ends pivoted upon the spindles of the roller *V'*, and thus forming a hinged joint to connect the plow to the lower front end of the elevator.

Z represents a pair of revolving colters or cutting-disks, which are journaled to the lower ends of arms *Z'*, that depend from the lower side of the plow-beam. These colters are located at a distance apart corresponding to the

width of the ditches to be excavated. The front end of the plow-beam is provided with a hook, which engages a ring, *a*, that is attached to the rear end of a draft-chain, *b*. 5 The said draft-chain passes through an eye, *c*, formed in the lower end of an elevating-rod, *d*, the said rod being similar to the rod *X*, and extending through a slotted plate, *e*, attached to the front end of the frame. The rod *d* is provided with a series of openings, *d'*. The chain *b* is adapted to be attached to a hook or pin, *f*, which projects from the front end of the frame, and the rod *d* is secured at any desired vertical adjustment by means of a transverse pin, 10 which passes through one of the openings *d'* and bears upon the plate *e*. By this means it will be readily understood that the front end of the plow-beam may be readily raised or lowered. 15 The hand-lever *I*, which is hinged to the sliding block *G*, has a vertical transverse opening, through which the elevating-rod *X* passes, and through the said opening, and also through one of the openings *X'* of the rod, extends a 20 transverse pin, which locks the rod *X* to the lever *I* at any desired vertical adjustment. By moving the lever up or down it will be readily understood that the rear end of the plow-beam, or, rather, the plow-standards carrying 25 the plow, and also the lower end of the endless elevator, may be raised or lowered. As the block *G* is adapted to slide longitudinally in the frame of the machine, the elevating-rod *X* is always maintained in a vertical position, 30 no matter to what depth the plow and lower end of the elevator may be lowered. 35 *g* represents a carrier-trough, which is supported on the arms *S²* of the brackets *S*. At one end of the said trough is journaled a roller, *h*, and at the opposite end thereof is a similar roller, *i*. An endless belt or apron, *k*, connects the rollers *h* and *i* and forms the bottom for the trough. 40 *l* represents a pair of depending bracket-arms, which are attached to the right-hand beam *B*, near the rear end thereof, and in the said bracket-arms is journaled a shaft, *m*. The rear end of this shaft *m* is connected to the forwardly-projecting spindle of the roller *h* by 45 means of the sliding sleeve-coupling *n*, and to the front end of the said shaft is attached a gear-pinion, *o*, which meshes with the wheel *P*. 50 The operation of my invention is as follows: The machine is drawn by a team attached to

the draft-pole that is hinged to the front axle, 55 one of the horses walking on one side of the ditch and the other walking on the opposite side thereof. The plow and the lower end of the elevator are lowered to the ground, and the rotating cutting-disks or colters cut the 60 sides of the ditch and the plow cuts the bottom thereof; and as the said plow is inclined rearwardly and upwardly, the earth which is excavated thereby is carried up and delivered onto the lower end of the elevator. This elevator is operated in the direction indicated by the arrows in Fig. 3 by being geared to the wheel *O*, as previously described, and delivers the earth onto the transverse carrier at the 65 rear end of the machine. The said carrier is 70 operated in the direction indicated by the arrows in Fig. 2 by being geared to the wheel *N*, as previously described, and thus carries the dirt which is excavated from the ditch and deposits it on one side thereof. 75

Having thus described my invention, I claim—

1. In a ditching-machine, the combination of the elevator having its rear upper end pivoted or hinged to the rear end of the machine-frame, the plow having its rear end pivoted or hinged to the lower front end of the elevator, the sliding block *G* on the machine-frame, the vertical rod *X*, extending through the said block and having its lower end attached 85 to the rear end of the plow, and the hand-lever *I*, pivoted to the sliding block and connected to the elevating-rod *X*, substantially as described.

2. In a ditching machine, the combination of the frame *A*, having the driving and supporting wheels, the plow suspended from the said frame, the lever to raise and lower the rear end of the plow, the vertically-movable rod *d*, depending from the front portion of the frame, and the chain *b*, attached to the front end of the frame, passed through a ring or opening in the lower end of the rod *d*, and having its rear end connected to the front end of the plow, for the purpose set forth, substantially as described. 90

In testimony that I claim the foregoing as my own I have hereto affixed my signature in presence of two witnesses.

WILLIAM THOMAS FINNELL.
